(57) **CLAIM**

I claim the ornamental design for a hair styling apparatus, as shown and described.

DESCRIPTION

FIG. 1 is a front perspective view of a hair styling apparatus, showing my design, shown in a closed position of use;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof;

FIG. 8 is a front perspective view thereof, shown with the jaws in a closed position and the tong in an open position of use;

FIG. 9 is a top view thereof;

FIG. 10 is a bottom view thereof;

FIG. 11 is a right side view thereof;

FIG. 12 is a left side view thereof;

FIG. 13 is a front view thereof;

FIG. 14 is a rear view thereof;

FIG. 15 is a front perspective view thereof, shown with the jaws in an open position and the tong in a closed position of use;

FIG. 16 is a top view thereof;

FIG. 17 is a bottom view thereof;

FIG. 18 is a right side view thereof;

FIG. 19 is a left side view thereof;

FIG. 20 is a front view thereof;

FIG. 21 is a rear view thereof;

FIG. 22 is a front perspective view thereof, shown with the jaws and tong in an open position of use;

FIG. 23 is a top view thereof;

FIG. 24 is a bottom view thereof;

FIG. 25 is a right side view thereof;

FIG. 26 is a left side view thereof;

FIG. 27 is a front view thereof; and,

FIG. 28 is a rear view thereof.

(Continued)

In the drawings, the broken lines represent portions of the article which form no part of the claimed design.
